(57) **CLAIM**

The ornamental design for a dishwasher panel, as shown and described.

DESCRIPTION

FIG. 1 is a perspective view of a dishwasher panel showing my new design; and,

FIG. 2 is a front view thereof. The broken line showings of the top surface rectangle and region therein in FIG. 1 and interior handle details in FIG. 2 are for environmental purposes only and form no part of the claimed design.

1 Claim, 2 Drawing SheetsFIG. 1

FIG. 2
